UNITED STATES PATENT OFFICE.

GEORGE F. SISBOWER, OF EAST ORANGE, NEW JERSEY, AND LOUIS E. PITTONI, OF NEW YORK, N. Y., ASSIGNORS TO NEW YORK COUCH BED COMPANY, OF NEW YORK, N. Y., A CORPORATION OF NEW YORK.

EXTENSION-COUCH.

1,271,955.

Specification of Letters Patent.

Patented July 9, 1918.

Application filed August 21, 1914. Serial No. 857,901.

To all whom it may concern:

Be it known that we, GEORGE F. SISBOWER, a citizen of the United States, residing at East Orange, in the county of Essex and 5 State of New Jersey, and LOUIS E. PITTONI, a subject of the King of Italy, residing at New York city, county of New York, State of New York, have invented certain new and useful Improvements in Extension-10 Couches, the following being a full, clear, and exact disclosure of the one form of our invention which we at present deem preferable.

For a detailed description of the present 15 form of our invention, reference may be had to the following specification and to the accompanying drawing forming a part thereof, in which—

Figure 1 is a perspective view of our 20 couch, and

Fig. 2 an end elevation thereof.

Our invention involves an extension couch having couch frames, one stationary, the other movable, with an operating device 25 to open and close the couch and a two-part mattress, together with a separate operating device for opening and closing the mattress, whereby the shifting of the two couch frames is a separate and independent operation from the shifting of the two mattress 30 parts or sections.

In the drawing, A represents a stationary couch-frame and B a movable couch-frame, the latter being arranged to telescope into 35 the former so that it may be drawn out to form a double bed, or pushed in to form a single bed. The frame A has its four legs resting on the floor while the front legs b^1 of the frame B rest on the floor and the 40 back legs b^2 , which are much shorter, travel on cross-bars a of the stationary frame. The operating device for the two couch-frames consists of a lever C pivoted to one leg of the stationary frame and connected 45 by link D to the movable section B. There is, of course, such a lever at each end of the couch.

A two-part mattress is provided, one part F resting on the stationary frame, and the

other part G adapted to either be on the 50 first part, as shown in Fig. 1, or to be moved out to lie on the movable couch-frame as shown in Fig. 2. The mattress is operated separately from and independently of the 55 operation of the couch-frames by means of a separate and independent operating device which consists of a bar H secured to the side and two ends of the movable part G of the mattress, the two end portions being turned down so as to have an offset pivotal 60 connection with ears h formed on the inner extremities of the end bars of the stationary frame A. This bar acts as a carrier-frame for the mattress-part G. Assuming the couch-frame B to be first drawn out, as 65 shown in Fig. 1, by means of the operating lever C, then the mattress can be operated separately and independently by taking hold of bar H and turning it, together with the part G of the mattress which is secured 70 thereto, over into the open position shown in Fig. 2. The mattress-part G then lies on frame B and the part F on frame A. Conversely, the couch being open, mattress-part 75 G will first be turned over as a separate and independent operation into the position shown in Fig. 1, where it lies on top of part F on frame A. Then, as a second and independent operation, the couch frames will be worked by lever C to draw frame B into 80 frame A.

By this means we greatly simplify and render certain and easy the entire operation of the couch. The relation of parts is such that the couch frames can be operated with 85 one hand and the mattress parts by the other hand of a person standing at one end of the bed.

What we claim as new and desire to secure by Letters Patent is:

A two-part extension couch comprising stationary and movable frame members, the end bars of the stationary member having lugs projecting from their inner extremities, a folding mattress consisting of a stationary part and a movable part, and an operating device for the mattress movable independently of the relative movement of

said frame members, said operating device consisting of a frame bar lying along one side and two ends of the movable part of the members and secured to one side thereof, the end portions of said operating device having offset members pivotally connected with said lugs.

In witness whereof we have hereunto set

our hands, before two subscribing witnesses, this 19th day of August, 1914.

GEORGE F. SISBOWER.
LOUIS E. PITTONI.
